UNITED STATES PATENT OFFICE.

LEMUEL P. FAUGHT, OF FOXBOROUGH, MASSACHUSETTS.

IMPROVEMENT IN MACHINES FOR PRESSING HAT-FRAMES.

Specification forming part of Letters Patent No. 130,031, dated July 30, 1872.

To all whom it may concern:

Be it known that I, LEMUEL P. FAUGHT, of Foxborough, in the county of Norfolk and State of Massachusetts, have invented an Improvement in Machines for Pressing Hat-Frames; and I do hereby declare that the following, taken in connection with the drawing which accompanies and forms a part of this specification, is a description of my invention sufficient to enable those skilled in the art to practice it.

The invention relates to the construction of a press or machine particularly designed for forming hat-frames of buckram, millinet, lace, or other suitable material used for hat or bonnet frames. In the invention I use, in combination with a die or former-block having the shape to be imparted to the crown and rim, a pair of open-and-shut die-jaws, jointed to a plate which is attached to a vertically-sliding cross-head, said jaws being so constructed and arranged that as they descend they keep open until they reach nearly to the rim of the former-block, and then automatically close upon the former-block, pressing and shaping the cloth laid upon the former-block, while when the cross-head rises the jaws automatically open, leaving the shaped frame upon the former-block. The invention consists, primarily, in combining with the former upon which the frame is shaped open-and-shut die-jaws, which first descend toward and over the former-block, and then automatically close inward (laterally) upon it, and which automatically open as the jaws rise.

The drawing represents a machine embodying my improvements.

A shows an end view of the machine. B is a sectional elevation of it. C is a front view of it. D is a plan of it.

a denotes a base, from which extend uprights b, which support a cross-beam or bed-plate c. Upon this plate rests the former d, composed of the rim-piece e and the crown-shaping block, which block may be solid or in one piece, but for bell-shaped crowns is preferably made sectional, with a center fixed block, f, and two side blocks g h; the center block f being made with inclined sides, so that the block tapers toward the top, and the side blocks with inclined faces resting and sliding upon the faces of said center block, so that by

moving them upward the diameter of the block is so decreased that the bell-crown formed thereupon, and which is smaller in the center of the body than at the top, may be easily removed. i denotes a cross-head, parallel to the beam e, and fixed to the tops of vertical slides k, that slide in the uprights b, the lower end of said slides being fixed to another cross-head, l, the slides k k and cross-heads i l constituting a vertically-reciprocating frame, which frame is jointed to a foot-lever, m, as seen at A, and is thrown down by pressure upon said lever, being raised by the stress of suitable springs n n, its elevated position being its normal position. Under and fixed to the upper cross-head i is a plate, o, to two opposite edges of which are hinged two former-jaws, p p. Each jaw p is preferably made with a straight outer edge, q, by which edge the jaw is hinged to the edge of the plate o, and, being thus suspended from these two opposite outer edges, the weight of the jaws causes them to fall apart or open, as seen at B, when the jaws are raised. They may, however, be separated, or their separation may be accelerated by the action of a spring; but I prefer that they should fall apart by their weight alone. When they open, the extent of their opening movement may be limited by any suitable device, the wire r, hooked at its ends and passing through eyes s, fixed to the jaws, answering well for this purpose. Each jaw is made with a projection, t, and under these projections are two inclines or arms, u, which, when the jaws descend, are struck by the projections t, forcing the jaws together and closing them upon the former-block, or upon the cloth laid over such block, the projections not striking the arms until the inner face of the jaws have nearly reached the rim of the block.

The whole operation is as follows: The cloth for the frame having been properly prepared is laid over the former-block, and the lever m is then pressed down, thereby carrying down the jaws, and causing them to close upon the cloth and force it against the former. The frame having been thus shaped upon the former-block, the pressure upon the lever is then withdrawn, and the stress of the springs will then throw up the lever and cross-head frame, and the jaws will open or fall apart, leaving the pressed frame upon the former-block ready

for removal, to effect which removal the block-sections $g\ h$ may be slid up sufficiently to so contract the former as to permit the shaped frame to be freely removed from it.

By these means the frames may be very rapidly and perfectly made, and no hand manipulation is required other than what is necessary to apply the cloth, raise the block-pieces $g\ h$, and remove the frame, the downward movement of the cross-head frame being produced by the action of the foot upon the lever, and all the other movements being automatic.

To prevent the formation of seams or folds upon the frame when the meeting faces of the jaws close upon it, flanges v may be employed,

which flanges shut beyond and break the joints.

I claim—

1. In combination with the stationary former d , the suspended shaping-jaws, which descend and automatically close upon the former, and which automatically open when they rise, substantially as shown and described.

2. The combination of the lever m , cross-head frame $i\ k\ l$, suspended jaws $p\ p$, and jaw-closing arms u , all substantially as shown and described.

LEMUEL P. FAUGHT.
